DESIGN FOR A VENTILATOR OR THE LIKE

Robert W. Rowland, Newark, N. J.

Application December 23, 1942, Serial No. 109,119

Term of patent 14 years

To all whom it may concern:

Be it known that I, Robert W. Rowland, a citizen of the United States, residing in the city of Newark, county of Essex, and State of New Jersey, have invented a new, original, and ornamental Design for a Ventilator or the Like, of which the following is a specification, reference being had to the accompanying drawing, forming a part thereof.

In the drawing,

Fig. 1 is a side elevational view of a ventilator or the like, showing my new design,

Fig. 2 is a top plan view thereof.

Fig. 3 is a bottom plan view thereof, and

Fig. 4 is a sectional view taken on line 4—4 of Fig. 1.

I claim:

The ornamental design for a ventilator or the like, as shown.

ROBERT W. ROWLAND.
